UNITED STATES PATENT OFFICE

2,377,986

UNIT AND MULTIPLE DOOR OPERATOR

Albert E. Weigle, Newark, N. J., assignor to National Pneumatic Company, New York, N. Y., a corporation of West Virginia

Application July 15, 1943, Serial No. 494,767

5 Claims. (Cl. 189—8)

This invention relates to door operating systems.

The general object of the invention is to provide a door operating system by means of which a plurality of doors may be controlled so that each individually may be power opened and power closed, or two or more of the group may be power opened and power closed, and including means whereby the doors which are normally locked may be individually unlocked and opened by hand.

The many detailed objects herein disclosed in combination with the above general object will be better understood from the following detailed description of the embodiment of the invention illustrated in the drawings. For this reason an extended list of detailed objects will not be separately given.

This invention resides substantially in the combination, construction, arrangement and relative location of parts, all as will be described in detail below.

In the accompanying drawings in which the same parts will be given the same reference numerals throughout the various views,

Figure 1 is a front elevational view of the operating mechanism associated with a single door, but which is duplicated for each of the doors of the group;

Figure 2 is an enlarged front elevational view of a portion of the mechanism illustrated in Figure 1, showing some parts removed or in cross-section; illustrating the parts in normal door closed and locked position;

Figure 3 is a simplified view of the mechanism associated with one door with some parts in cross section; illustrating the position of the parts when the door is moving to open position under power;

Figure 4 is a view similar to Figure 3 showing the door closed and locked but with the parts in position for manually unlocking and opening;

Figure 5 is a view similar to the last figure but differing in that the manual operation has begun and the door is unlocked;

Figure 6 is a view similar to the preceding view showing the manual operation continued further to effect after unlocking opening of the door under power, or, if air is turned off, by hand;

Figure 7 is a cross-sectional view taken on the line 7—7 of Figure 2;

Figure 8 is a cross-sectional view taken on the line 8—8 of Figure 2;

Figure 9 is a cross-sectional view taken on the line 9—9 of Figure 2;

Figure 10 is a longitudinal, central, cross-sectional view of the manually actuated unlocking mechanism;

Figure 11 is a longitudinal, central view through the motor control valve;

Figure 12 is an elevational view thereof;

Figure 13 is a side elevational view of the emergency lever;

Figure 14 is a front elevational view of a portion of the operating handle broken away;

Figure 15 is a diagrammatic and schematic illustration of the control system for the engines of two doors; and

Figure 16 is a perspective view of three of the cooperating levers forming part of the control mechanism.

The subject matter herein disclosed has been specifically designed for application to the operation of prison cell doors, but from the following description it will become apparent that it is not limited to such use, but can equally well be applied to the operation of door groups for other types of closures. As will appear from the description as it proceeds, the mechanism has been devised to provide great flexibility in the operation of a plurality of doors in a group either singly or as a unit or in any desired sub-combinations of the complete group while insuring against unauthorized opening and providing protection against faulty operation in an emergency.

There is illustrated in Figure 1 the mechanism associated with its door and duplicated for each door. The invention has been illustrated as applied to a prison cell and the grating front of the cell and the door frame are diagrammatically illustrated at 1. The wall above the door appears at 2 and lying between the grating and the wall is a casing 3 which is closed at the front by means of a sectionalized removable cover 3'. Each cover panel upon removal exposes the mechanism for one door and when in place protects it against tampering. The door 4 is mounted from above on roller hangers 5 so as to have a sliding movement with respect to the cell front. Attached to one of the hangers, as is clear from Figure 2, is a bracket 6 to which the piston rod 7 of a pressure fluid operated differential engine 8 mounted above the door is attached. An engine of this type suitable for the purpose with some obvious modifications is shown in United States Patent No. 2,089,932 granted August 17, 1937. At 9 is the pressure fluid supply line from any suitable source

which extends throughout the cell bank and is provided at each engine with branch connections 10 permanently connecting the center of the engine 8 with the fluid supply source, as is usual in the case of differential engines of this type. The branch 10 also extends to the pressure fluid supply connection of an electro-magnet valve 11 which has not been illustrated here in any detail since it is very well known in this art. An example of a suitable construction for a valve of this type 10 is illustrated in full detail in United States Patent No. 1,849,516 at Figure 38.

The fluid delivery line 12 from the valve when actuated extends to the locking cylinder 13 which comprises no more than a cylinder having a piston therein with a spring normally holding the piston to the right, Figure 2, so that the piston rod is withdrawn into the cylinder, as illustrated in Figure 2. Pressure pipe 9 is provided with a branch connection 14 extending to the engine control valve 15. The valve when in normal position (Figure 11) supplies fluid pressure through the branch 16 to the right hand end of the engine 8. The exhaust port of the valve 15 is connected by the branch 17 to the exhaust line 18. In a system of this type it is desirable to conduct the exhaust of the engines to some remote point rather than to permit its discharge directly into the atmosphere. Thus the exhaust connection 18 is provided for the equipment. The details of valve 15 are shown in Figures 11 and 12. The pressure supply pipe 14 connects to the port 14' of the valve which in turn is connected through the valve body to the port 16' of the valve to which the supply pipe 16 is connected. The movable valve member 34 is normally held in the position shown in Figure 11 by reason of the spring to maintain this connection until the movable valve member 34 is moved upwardly by applying pressure to operator 32, when the connection between pipes 14 and 16 is cut off and pipe 16 is opened to exhaust through the port 17' to which the exhaust connection 17 is made.

Supported over the door in any suitable manner are a pair of brackets 19 and 20 in which is mounted for longitudinal sliding movement, a bar 21 which has a hole 22 near one end adapted to register with the hole 23 in the bracket 19 when the bar 21 moves to the right. This bar is provided with a bracket 24 which is pivotally connected by the link 25 to one end of a double ended lever 26 (see Figure 2). The other end of this lever is pivotally connected to a rod 27 which runs along the cell bank so as to interconnect all of the levers 26 of the bank and to connect with the emergency lever of Figures 13 and 14 positioned at one end of the bank. Reference to this feature will be made later. As appears best from Figures 7, 8, 9 and 10, the double ended lever 26 is provided with a forwardly extending cup formation 26' and with a pin 26" mounted at the bottom of the cup in an eccentric position. The lever 26 is pivotally mounted on a sleeve supported in the housing 28 within which is mounted the valve 15 and other mechanism shortly to be described (see also Figure 2). At this point it will be noted that the key K can be passed through the holes 22 and 23 when they register so as to project into the cup 26' and engage the complementary shaped end of the shaft 44 to be referred to later. The removable panel 3' has a hole therein which always registers with the hole 23.

Referring to Figure 2, for example, it will be seen that the forward door hanger bracket is 75

provided with a forwardly extending latch bar 29 which when in door closed position, as illustrated in Figure 2, is engaged by the vertically reciprocable latch 33 which slides in a guide 30 having the housing 28. The compression spring 31 tends to hold the latch 33 in its latching position, as shown in Figure 2. At this point it will be noted that the latch 33 is positioned so that it may engage the operator 32 of the valve 15.

The piston rod of the lock cylinder 13 is pivotally connected to a link 35 which in turn is attached to a bracket 36, which in turn is pivotally connected to the upper end of the lever 37. This lever has a short lateral extension 37' and is pivotally mounted upon a shaft 38 mounted in the housing 28, all as is quite clearly illustrated in Figures 9 and 10. Pivotally mounted on the shaft 38, adjacent the lever 37, is a bell crank lever one arm 39 of which engages a radial slot in the upper end of the latch 33. The lever 39 is provided with a pair of lateral extensions 39' and 39'' lying on opposite sides thereof, as is clear from Figure 9, one of which 39' is positioned to be engaged by the short lateral lever 37' and the other of which is positioned to be engaged by a lateral extension 41' on a lever 41, also pivotally mounted on the shaft 38. The outer end of the arm 41 is right angled, as shown at 42. The other arm 40 of the bell crank lever extends in a generally downward direction, as will be seen from Figures 2 to 6 inclusive, and is arranged to engage the roller on the end of lever 43. The lever 43, as is clear from Figure 10, is secured to the shaft 44. The key end of the shaft is provided with a peripherally notched disc 45 which appears in several figures and positioned to cooperate with the pin 26". An overcenter spring operated toggle 46 is provided for the lever 43 to cause snap action and positioning thereof in accordance with well known principles for devices of this type.

It is of interest to note, as is clear for example from Figure 2, that the lever 41 has a pair of oppositely extending wings arranged to cover the slot in the housing 28 in which the arm operates and to maintain the slot closed at all times so that tampering with the equipment at this point is prevented.

On a stud 47 are pivotally mounted a pair of supports for the mercury switches 48 and 49. The support for the switch 48 has a downward extension 48' positioned to be engaged by an adjustable actuating screw 6' mounted on the upper end of the bracket 6 by means of which the engine is connected to the door. The support for the switch 49 likewise has an extension as shown at 49' positioned to be engaged by the bent end 42 of the lever 41. The supports for both of these switches are provided with springs and are shaped for cooperation with a fixed stop, as shown, to limit their counterclockwise rotation under the action of the springs. These switches are included in circuits to be shortly described. These circuits, in part at least, extend to the terminal board shown adjacent the switches in Figure 2.

Referring to Figures 13 and 14, there is illustrated the emergency lever which is to be mounted at either end of the cell bank within a cabinet, diagrammatically illustrated at LB in Figure 15, which may be locked against tampering. This device includes a suitably shaped support 50 upon which the manually actuated lever 51 is pivotally mounted at 51'. Integral with the lever is an extension lever 52 which is to be pivotally connected to the link 27 extending along the top of the cell bank, so as to interconnect all of the double ended

levers 26. The lever 53 includes a latch bar 54 which may be given longitudinal movement by means of a finger button 56 adjacent the handle of the lever 53. This latch cooperates at 54' with the notches formed on the support as indicated at 55. Thus the lever may take three different positions which may be termed for purposes of description normal position, first emergency position, and second or full emergency position (as shown in Figure 13). Mounted on the support 50 on a stud 57 is an oscillatable support 58 for the mercury switch 59. This support is integral with a lever 60 having a pin engaging in a slot in the arm 53, as clearly shown. Thus as the arm is moved the mercury switch may be tilted from an off position to an on position and vice versa.

The piping and wiring diagram is shown in Figure 15 for two doors. At a central control station, probably at the end of a cell bank and adjacent the emergency lever, is a door control panel diagrammatically illustrated at PB in Figure 15. Only sufficient of the panel is diagrammatically illustrated to describe the operation of the two doors shown, and as will appear later the parts illustrated will be duplicated depending upon the number of doors to be controlled. It is intended that this panel will be enclosed within a cabinet which has a door that can be closed and locked. A switch 71 is provided in the cabinet and operated by the door so that it is open when the door is closed. One terminal of this switch is connected, as illustrated, to the positive side of a current source by the supply lead 70. The other terminal of this switch is connected by the wire 72 to one side of the emergency signal lamp controlled by the switch and to a wire 91. The other side of the lamp 73 is connected by wire 74 to one terminal of the switch 59 mounted on the emergency lever. When this lever is in normal position this switch is open. The other contact of the switch is connected by wire 75 to the negative side of the current source through the supply lead 76. The group control switch is shown at 77 and is connected at one side to the supply lead 70. The other side is connected by wire 78 to one of the switch blades of each switch 79 and 80. The other switch blade of each switch is connected by wire 88 to the positive side of the current source. The fixed contacts of the switches 79 and 80 are respectively connected by the wires 86 and 83 to one terminal of the winding of the corresponding magnet valves 11. The other terminals of the windings of these valves are connected to the wire 85, which is directly connected to the supply lead 76.

Positioned adjacent each individual switch are lamps. For example, as illustrated, there is the lamp 81 for the switch 79, and 82 for the switch 80. One side of each of these lamps is connected by the common wire 89 to the current lead 76. The other lead of lamp 82 is connected by wire 90 to the mercury switches 48 and 49 which in turn are connected in series and back to the wire 91. Similarly the other terminal of lamp 81 is connected by a wire 100 through the mercury switches 48 and 49 in series for the other door and back to the wire 91. Switch 77 has two positions, that is, the open position as illustrated and the closed position when the wire 78 is connected to the supply lead 70. The manuals or operators of the individual switches 79 and 80 have three positions, that is, door closed, door open and group position. They are illustrated in group position of the operator so that operation of switch 77 would control both door engines to open and close

the doors. With the lower blade of each switch in the position shown the other blade is in door closed position so that in order to open each door individually the upper blade will be moved from the position shown that is, to door open position of the operator to engage the upper contact so that each door can be opened individually. When the upper blade is returned to the position shown the door will close provided the group switch is open. In order to disconnect any switch and associated equipment from group control the lower blade of the switch is moved to open position that is to door closed position of the operator whereupon the control of the group switch there-over is interrupted. Thus the operator for the individual switches can take three positions to accommodate the operating positions of the switches. These positions would be the group position, which is the position shown, and the door open position in which each blade engages its contact and door closed position in which each blade is out of contact as described above.

The flexibility of this system will be apparent from the following description of the several ways in which the equipment may be operated to open and close the doors individually or in desired groups by means of power, and individually unlocked and opened, and closed manually.

Before describing these operations in detail a few general observations will be helpful. The emergency signal light 73 is illuminated when the emergency lever 53 is in the first emergency and in the full emergency positions. The panel box door operated switch 71 is so arranged that when the door is closed the switch opens its contacts making the signal light system inoperative and extinguishing all signal lights. When the control panel of the cabinet door is open this switch closes its contacts and the signal light system becomes operative.

The wiring circuits are so arranged that when the individual and group switches 79 and 80 are in their door closed positions all door control switches are dead and there is no possible way of operating the doors except from the control cabinet or by means of the emergency unlocking lever 53. Under this condition the doors are all closed and locked. In a practical installation using air under a pressure of 85 pounds per square inch when opening the doors the engines each exert an actual pull of 225 pounds which effectively prevents holding a door closed by hand. During the closing the engines exert a pressure of about 25 pounds preventing injuries to one if caught by the doors. Cushioning devices are provided to prevent slamming on opening and closing.

The normal condition of the system

In the normal condition of the system all doors are closed and locked. To obtain this condition the apparatus is positioned as follows:

1. The emergency, unlocking and control lever 53 is in its normal position, extreme left. As a result the keyholes 22 in the bars 21 are out of alignment with the keyholes 23 in the brackets 19 and the bars 21 are locked in that position so that the system cannot be operated by means of keys.

2. All individual switches 79 and 80 should be in their group position which is the position shown in Figure 15.

3. The group switch 77 must be in door closed position which is the position shown in Figure 15, and the door of the control panel cabinet is closed and locked.

To open any individual cell door

1. The emergency lever 53 is in normal position.
 2. The control cabinet is unlocked and its door is opened. Each of the lights 81 and 82 positionally associated with the switches 79 and 80 respectively should light up when the cabinet door is opened. If one or more of these lights are not energized it is at once necessary to investigate the condition of the cell doors and locking system to determine whether they have been tampered with. If everything is in normal position these lights will be illuminated through the following circuits. From wire 10 through switch 71 which closes when the door of the cabinet is opened, to wire 81, through the closed switches 48 and 49 at each door, and back by the wires 80 and 100 through the respective lamps 82 and 81, to the common lead 89 back to the circuit wire 78. If the mechanism has been tampered with to the extent that one or the other of the switches 48 and 49 of one or more doors have been opened the corresponding light 81 and 82 at the panel will not be energized. At this point it will be well to recall that the above and following description contemplates that the various circuits and operations described will be duplicated for as many doors as may be desired in a cell block or group.

3. The individual switch 79 or 80 corresponding to the cell door to be individually opened is moved to door open position energizing the corresponding door lock magnet valve 11 to supply air to the lock cylinder 13. This is accomplished by moving the switch operator to door open position which moves the upper blade of switch 79, for example, completing a circuit from wire 78 through wire 88, upper blade of switch 79, wire 86 to the left hand magnet valve 11 and back by wire 87 to wire 85 and thence to wire 78. Thus the magnet valve is operated to connect pipe 10 to pipe 12 and supply pressure fluid from the supply line 9 to the lock cylinder 13. The piston of the lock cylinder 13 is moved to the left (Figure 3) causing through the link 35, the lever 37 to move from the normal position shown in Figure 2 to the position shown in Figure 3. Its extension 37' engages the adjacent wing 38' of lever 38 (see Figure 9) raising arm 38, which in turn lifts the latch 33 to the position shown in Figure 3 and compresses spring 31. At the upper end of the movement of latch 33 the operator 32 of the door engine control valve 15 is operated to disconnect supply pipe 9 to shut off the supply of pressure fluid through the valve 15 to pipe 16 and to connect pipe 16 to exhaust through the valve 15 and branch 17 to the exhaust line 18. Thus the large or right hand end of cylinder 8, Figure 1, is connected to atmosphere while, of course, the pressure fluid connection through the branch 10 is maintained. The result is that the piston will move to the right withdrawing the piston rod 7 into the cylinder and pulling the door 4 open.

4. As the door was unlocked by the upward movement of latch 33, the extension 38", Figure 16, on the lever 38 engaged under the lateral extension 41' on the lever 41 also raised that lever so that its bent end 42 engages the lug 48' of switch 49 tipping it to the position shown in Figure 3 and extinguishing the associated signal lamp 81, indicating that the door is unlocked. As the door opened the screw 8' on the bracket 6 moved back freeing the lug 48' so that switch 48 also moved from the closed position in Figure 2 to the open position in Figure 3 further breaking the circuit to the same signal light.

5. In order to close this door which has been opened, switch 79 is moved back to the position shown, breaking the circuit to the magnet valve 11 so that the lock cylinder 13 is opened to exhaust, whereupon the spring in the cylinder will return lever 37 to normal position and aided by spring 31 to return also the latch 33 to latching position, whereupon valve 15 returns to the position shown in Figure 11, so that the right hand end of the large cylinder of engine 8 is cut off from exhaust and connected to the pressure line 9, whereupon the engine will close the door. The return of lever 37 to normal position permitted lever 41 to fall back to normal position so that the switch 49 controlled by it closes. As the door closes and moves into latched position, screw 6' will operate the switch 48 to close it, so that light 81 will again be energized indicating that the door is both closed and locked. The shape of the latching bar 29 secured to the door is such as to ride the latch 33 up on its end until it snaps into the seat provided for it. It will be noted that the signal light associated with each individual door will not be energized until the door is both fully closed and locked. Only in the event that both of these conditions exist will the light be energized. At any time during either the opening or closing of the door the operator may be manipulating the individual switch, stop the movement of the door and cause it to close or open.

To close any single door that was previously opened with individual control

35 1. The emergency locking lever 53 is in normal position.
 2. The group switch 77 must be in door closed position as shown.
 3. The panel cabinet door is unlocked and opened.
 4. All individual lights 81, 82 should be illuminated for the doors supposed to be closed and darkened for the doors supposed to be open.
 5. The operator moves the individual switch 79 or 80 to its group position, de-energizing the door lock magnet valve 11 as previously described. It in turn exhausts air from the door lock cylinder and the spring loaded latch bolt 33 returns to door locked position. This allows the door engine valve 15 to connect pipe 16 to the pressure supply so that pressure fluid is allowed to enter the larger cylinder of the engine causing the door to close. As before locking occurs by raising the latch bolt against the spring 31 which snaps back to locking position at the right time. As before the switches 48 and 49 ultimately close to energize the individual light 80 or 81, indicating completion of the operation.
 6. If the operator during the closing of the door returns the individual switch to door open position, the door will reverse and open.

To close any single cell door that was previously opened by a group control

65 1. The emergency unlocking lever 53 is in normal position.
 2. The panel cabinet is unlocked and opened.
 3. All individual lights for the doors supposed to be closed, which means that their individual switches 80 and 81 are in door closed position, should be illuminated while the others should be darkened.
 4. The doors supposed to be open will then be individually closed by operating individual

switches 78 and 80 to door closed position to close the door as previously described.

5. The operator may during closing of any door return the individual switch to group position to cause the door to re-open.

To open any group of cell doors or all cell doors simultaneously

1. The emergency unlocking lever 53 is in normal position.

2. The control panel cabinet is unlocked and opened.

3. If all the doors are to be opened all the individual switches 78 and 80 must be in their group position which for reminder it is noted is the position shown in Figure 15. If, however, it is desired that some of the doors not open, the corresponding individual switches must be moved to door closed position, which means that the lower blade thereof is moved out of engagement with its contact so that both blades of that switch are open.

4. After setting the individual switches if any doors are to remain closed the operator closes switch 77 which causes all of the doors of the group, or those in which the individual switches are in group position, to open. For this function a circuit is completed from wire 70 through closed switch 77 (its door open position), through wire 78 and through the lower blade of each individual switch in group position by wires 83 and 86 to the corresponding magnet valves and back by wires 84 and 87 to wire 85, and thence to wire 76.

5. As these doors unlock the corresponding lights 81 and 82 will darken.

6. If the operator returns the group switch 77 to door closed position, that is opens it, all of the doors will close. The same result follows if switch 77 is opened while the doors are opening, that is they will stop and move back to closed position.

To close any group of cell doors or all cell doors simultaneously when the doors were opened by group control

1. The emergency locking lever 53 is in normal position.

2. The operator unlocks and opens the control panel cabinet.

3. If all doors are to be closed all individual switches 78 and 80 must be in their group position as shown in Figure 15. However, if some doors are to remain open these individual switches are operated to door open position.

4. After setting the individual switches the operator places the group switch 77 in door closed position, that is he opens it and all or the selected doors close simultaneously.

5. The individual lights 81 and 82 will be illuminated as each door is closed and locked. Those that do not so illuminate should be investigated to determine the cause.

6. If the group switch 77 is returned to door open position all the doors will reverse their movement and open during closing as well as when fully closed.

To close any group of cell doors or all cell doors simultaneously when the doors are opened by individual control

1. The emergency locking lever is in normal position.

2. The operator unlocks and opens the control panel cabinet door.

3. If any doors are closed and must remain closed the individual switches for these doors must be in door closed position.

4. The group switch 77 must be placed in door open position.

5. The individual switches for doors to be closed are then placed in their group positions.

6. The operator places the group switch 77 in the door closed position and the doors selected 10 will close simultaneously.

7. The corresponding lights for all selected doors to be closed will be illuminated as each door closes and locks. If this does not occur irregular operation is indicated.

15 8. If the operator returns the group switch to door open position while the doors are closing, or after they have closed they will open.

Reversal of doors

20 1. If the cell doors are moving under the control of the group switch the operator can reverse any individual door by moving the individual switch to the position opposite to the movement of the group.

25 2. If the cell doors are moving under the control of the group switch they can all be reversed by reversing the position of the group switch.

3. Any cell door moving under individual control can be reversed by reversing the position of 30 the individual switch.

Emergency unlocking control lever

This lever has three positions as previously mentioned. Normal and first emergency and 35 full emergency positions successively.

1. When the emergency unlocking control lever is in normal position the doors can only be controlled from the control panel. At this time the keyholes are all covered.

40 2. When the emergency unlocking control lever 53 is in the first emergency position all doors are locked but the keyholes are uncovered and the special key K can be inserted. This results from the fact that as the lever 53 is moved to first 45 emergency position the connection 27 to the upper end of lever 52 (see Figure 13) shifts the bars 21 to the right (Figure 1) to align the pairs of holes 22, 23. If the air pressure system is in normal operating condition the doors will open when they are individually unlocked by means of the key. The alignment of the pairs of holes 50 22, 23 is illustrated in Figure 4. All the parts are otherwise in normal door closed and locked position. When the key is inserted and turned 55 as illustrated in Figure 5, the lever 43 is moved to the right and engaging arm 40 of the bell crank as it does its other arm 39 is raised unlatching the door. Continuing the operation by means of the key to the position shown in Figure 6 the latch 33 is raised to the point where valve 15 is operated and switch 49 is opened.

60 The operation of valve 15 exhausts the engine and the door will open under power. As it opens, of course, switch 48 also opens. The notched plate 45 and the pin 26 limit the movement of 65 the parts as effected by the key K in an obvious manner. If the air pressure has failed for any reason the doors can be opened by hand when the parts have been moved to the position shown by Figure 6, which movement is sufficient only to unlock the doors. It will be noted, of course, that while the operation of the lever 53 has shifted all the bars 21 to align the hole pairs 70 22, 23, the doors are individually operated by 75 the key.

As soon as the emergency lever 53 was moved from normal position to either emergency position, switch 59 closed, see Figure 15, to energize the emergency light and keep it energized, indicating that the lever is out of normal position.

It will be seen then that with the lever 53 in first emergency position each door may be individually unlocked and locked, opened and closed by hand if there is no air, or opened and closed by power if the air system is in operating condition.

When the lever 53 is in full emergency position a locking device, not shown, is unlocked to permit the removal of the cover panels 3' so that access to the equipment of each door may be had for authorized purposes. Only when the lever 53 is in full emergency position is it possible to remove these cover panels. At this time all doors are unlocked because pin 28" engages the end of the notch in plate 46 and thus turns the shaft 44 to unlock position.

3. When the lever 53 is placed in full emergency position and then returned to first emergency position all doors will be unlocked because spring 46 keeps shaft 44 in the position to which it was turned by pin 28" in full emergency position and the hole pairs will be aligned. The panel fronts will be locked in place and the doors may be individually locked with the key K. In order to lock all the doors the emergency lever 53 must be placed back in normal position.

From the above description it will be apparent to those skilled in the art that the subject matter of this invention is capable of considerable variation without departing from the novel combinations and functions herein disclosed. I do

not, therefore, desire to be strictly limited to the disclosure as given herein but rather only as required by the claims granted me.

What is claimed is:

5 1. In a door control system a plurality of doors, engines respectively connected to said doors, means for locking each of said doors in closed position, individual engine control devices, individual lock control devices, said locking means individually actuating the respective engine control devices, sources of energy for said engines and lock control devices and group control devices cooperating with said lock controlling devices whereby the doors may be selectively unlocked, and opened and closed and locked individually, as a group or as sub-groups.

10 2. In the combination of claim 1, said engines being differential fluid pressure engines and said lock control devices being pressure fluid operated.

15 3. In the combination of claim 1, said engines being differential fluid pressure operated engines supplied continuously with pressure fluid when the doors are closed and said engine control devices when actuated opening the ends of the cylinders in which the larger faces of the piston are exposed to exhaust whereupon the doors open.

20 4. In the combination of claim 1, means for manually unlocking said doors individually, and means controlled by a single operator for rendering said manual unlocking means accessible or inaccessible.

25 5. In the combination of claim 1, signal devices cooperating with the doors and locking means to indicate when the doors are closed and locked and when they are unlocked and/or open.

30 35 ALBERT E. WEIGELE.
